UNITED STATES PATENT OFFICE.

ROBERT P. HERON, OF SYRACUSE, NEW YORK.

BUFFER.

1,137,138.

Specification of Letters Patent. Patented Apr. 27, 1915.

Application filed August 2, 1909. Serial No. 510,789.

To all whom it may concern:

Be it known that I, ROBERT P. HERON, a citizen of the United States of America, and a resident of Syracuse, in the county of 5 Onondaga and State of New York, have invented certain new and useful Improvements in Buffers, of which the following is a specification.

My invention relates to buffers for attachment to the feet and backs of chairs and for use with other furniture where a wearing surface of great durability is desired and where it is preferred not to use casters. For the wearing or contact surface of this 15 buffer I use a block of compressible material preferring to employ for this purpose hard felt which is compressed into a hard button. Felt is very well suited to this purpose since it is noiseless, is very durable, 20 does not in any way injure the floors, may be made sufficiently hard to endure the weight put upon it, and being water proofed as by cravenetting is not subject to injury from water or antiseptic solutions used in 25 cleaning the floors. While these buffers are particularly useful in connection with furniture and especially as feet or dumb casters therefor, they may be employed for various other purposes, for example, on the soles of 30 shoes, on the ends of crutches, as door checks, etc. It will be apparent therefore that I employ the word "buffer" as a broad term for my device whether it is used primarily to lessen the shock of impact, to prevent shock, noise 35 or injury by impact or contact, or for other useful purposes for which it is adapted. It will be obvious also that the buffer need not be circular or cylindrical but that it may be oblong or of any other desired shape. 40 One of the principal objects of my invention is to so utilize felt in such a buffer, pad or tip as to secure all its natural advantages. To this end I employ in making the buffer unsized felt, *i. e.*, felt containing no glue or 45 other stiffening agent which destroys those characteristics on account of which it is desirable to use felt and makes it stiff and harsh so that it tends to scratch and injure the surface with which it contacts. By compressing the unsized felt until it is very 50 hard and retaining it in the position to which it has been compressed I secure the qualities aimed at by sizing yet without any of the ill effects thereof.

55 My buffer differs radically from any other

of which I have knowledge in that the compressible material of which its body is made is compressed in and through a retainer and held by suitable means in the position to which it has been compressed. The details of the construction and the method of making the buffer will more fully appear later on in the specification. 60

While I have illustrated several embodiments of my invention, I wish it to be understood that I do not limit myself to the said embodiments. Indeed this will be readily apparent from the claims appended hereto. 65

Referring to the drawings: Figure 1 is a perspective view of the finished buffer. Fig. 2 is a perspective view of the parts which make up the buffer shown in disassembled position. Fig. 3 shows the disk struck from the stock before it has been formed into the 70 retainer. Fig. 4 illustrates the method of making the buffer showing the finished buffer and just enough of the press to make the method clear. Fig. 5 is a perspective view of the parts which make up a modification 75 of my buffer designed particularly for use as a foot for metal furniture, the parts being shown in disassembled position. Fig. 6 is a perspective view of the finished buffer 80 of the parts of which are illustrated in Fig. 5. Fig. 7 is a perspective view of a modified 85 form of buffer having a prong and designed particularly for use on small furniture. Fig. 8 is a section through the buffer shown in Fig. 7. Fig. 9 is a perspective view of 90 the preferred form of the buffer. Fig. 10 is a perspective view of the parts which make up the form of buffer illustrated in Fig. 9, the parts being shown in disassembled position. Fig. 11 is a plan view showing the disk struck from the stock before it has been formed into the retainer for the 95 preferred form of buffer. Fig. 12 shows three different forms of blanks for the 100 pronged attaching plate. Fig. 13 is a perspective view of the preferred form of my buffer adapted for use especially as a small chair tip where, by reason of its small size, a large number of attaching prongs are unnecessary. 105

As suggested by the modifications illustrated the attaching means may vary widely and the retainer may also be varied. However, it will be noted that the retainers used in the forms of the device shown in the first 110

eight figures are of substantially the same construction. This retainer will now be described.

Referring to Fig. 3, 1 is the disk struck from the stock and constituting the blank from which the retainer cup is stamped. This disk 1 is drawn in a well known way to form the retainer cup having the hole 2 through its bottom, the edge pressure-resistant flange 3 and the upstanding flange consisting of the points 4 and the retaining lugs 5 separated from the former by spaces 6. 7 is the disk of compressible material from which I form the pad or cushion. This disk I make of very hard unsized felt of a diameter to fit within the retainer cup and of a thickness about the same as the depth of the cup or somewhat greater, the thickness necessary depending on the degree of hardness of the felt disk and being sufficient to secure in the wearing button the desired thickness and hardness. A backing plate 8 of the same diameter as the disk is provided. The cup below the line of fold may be made relatively shallow to save metal and to insure a high degree of compression. The metal parts above referred to are preferably of sheet steel and have great strength and rigidity. Where the buffer is to be used on light furniture and where great strength is not required some other metal as brass may of course be employed.

Various different means for attaching the buffer are illustrated. As shown in Fig. 1 the points 4 may be left upstanding and will then serve as attaching means, it being readily possible to drive the buffer into the material of the article to which it is to be attached. Where this cannot be done owing to the nature of the material some other attaching means is obviously necessary and to adapt the buffer to metal furniture it has been modified as shown in Figs. 5 and 6 by the addition of a socket tube. The modification illustrated in Figs. 7 and 8 is provided with a center prong so that it may be driven like a nail into the wood or other relatively soft material to which it is to be secured.

Referring to Figs. 5 and 6 the retainer, 50 felt disk, and backing plate are the same as the corresponding parts in Fig. 2 and bear the same reference numerals. In addition a socket tube 15 is provided. This tube is stamped out of sheet metal and has lugs 16 at its lower end. Its upper part is provided with slits 17, and the upper end of the tube is turned inwardly slightly at 18 to enable the buffer to be readily inserted in the socket in the furniture leg. When assembled the 60 lugs 5 are bent down on the lugs 16 and the intermediate points 4 instead of being left upstanding to constitute attaching means are also bent down upon the lugs 16 or between them, or they could be bent down upon the 65 plate 8 between the adjacent lugs.

Referring to Figs. 7 and 8, the retainer and disk are numbered correspondingly to the same parts in the other figures. In this form of the buffer the attaching means consists of a tack 19 constituting an attaching prong which projects through the backing plate against the under side of which its head 20 rests. The backing plate together with this tack is held permanently in position by means of the lugs 5, and the intermediate points 4 are also turned down upon it. This form of buffer is suitable for use for light furniture and may be made of sheet brass or other relatively soft material.

Figs. 9 to 13 illustrate the preferred form of my invention. In this form I employ a different attaching means, and am able to save metal by using a shallower retainer. This will more clearly appear from the following description: The retainer, as in the other forms, is provided with the flange 3 and has the hole 2 in its bottom. This retainer is stamped from the disk 1' (see Fig. 11) in the same manner that the retainer of the other forms of the device is made. For convenience in bending, the outer edge of this disk which in the retainer becomes the upper edge is shown as provided with serrations 21. It might, however, have an unbroken edge. As in the other forms a block of felt 7 is compressed in and through the retainer and held in position. The fastening means consists of a pronged plate three forms of which, designated by the reference numerals 22—23 and 24, are shown in Fig. 12. Each of these is provided with prongs 25 which (as shown in Figs. 9, 10 and 13) are bent up at right angles to the plate. The backing plate 8' has a central raised portion 26 which is surrounded by a narrow flange in a somewhat lower plane. The raised portion 26 is provided with holes 27 through which the prongs 25 are inserted, the plate carrying the prongs occupying the space within the raised portion. The upper edge of the retainer is bent down upon the edge of the backing plate 8' which it will be recalled is in a somewhat lower plane than the raised portion. This arrangement not only locates the attaching plate firmly and conveniently, but forms a desirable finish, the bent over teeth forming the edge of the retainer being in substantially the same plane as the upper surface of the raised portion. The attaching prongs in this construction are firmly held and are an efficient means for attaching the buffer which may be driven in like an ordinary nail. The blank 22 is less wasteful of metal than the blank 24. The difference in these blanks results in a different angle of the face of the prongs. The plate 23 is suitable for use in small buffers such as are used for tips on small chairs. The use of a plurality of prongs affords a much securer fastening

than does a single one and each is firmly backed.

The method of making the buffer shown in Fig. 1 will be clear on reference to Fig. 4, and it will be apparent that the modifications shown in Figs. 6 and 7 are made in substantially the same way. The buffer of Fig. 1 is made by placing the dry felt disk in the retainer, laying the backing plate upon the back of the disk, and forcing the plate and disk into the retainer which action compresses the edge of the disk against the pressure-resisting flange of the retainer, causes the part of the disk opposite the central hole to be forced through it, thus forming a hard button, and bends the intermediate lugs on the flange down upon the backing plate to hold the parts firmly in place. This will appear more in detail from Fig. 4 of the drawings in which the completed buffer is shown in place in the press. The parts being assembled in the press, the plunger 9 pressed by the stiff spring 10 and movable with the upper die 12 forces the backing plate 8 and felt disk 7 into the retainer compressing the edges of the disk against the retaining flange 3 and forcing the middle of it through the hole 2 in the bottom of the retainer and into the lower die 11. The upper die 12 is provided with holes 13 which receive the attaching points 4 without bending them and with intermediate curved portions 14 which bend the intermediate retaining lugs 5 inward and fold them down upon the top of the backing plate 8. This is done rapidly and effectively in one operation so that only three machine operations all told are necessary in making the buffer. The lower die is effective in forming a button of the desired shape. It is obvious that to secure greater compression more than one press might be used, only the last turning down the flange and each press having a deeper die than that of the press preceding it.

The buffer shown in Figs. 5 and 6 is made in the same way except that the socket tube is assembled with the other parts and secured thereto. In this case the intermediate points 4 are bent down as well as the lugs 5. To secure this result the holes 13 in the upper die are omitted. The plunger is provided with a socket to receive the socket tube and with a curved portion to turn in the top edge of this tube. It may have also a centering pin.

In making the buffer shown in Figs. 7 and 8 the entire flange is bent down on the backing plate. The plunger is constructed to receive the prong 19. Otherwise the method is that previously stated.

The method of making the buffer shown in Figs. 9 to 13 is substantially that already stated. The attaching plate with its prongs 25 is assembled with the backing plate.

These parts are then placed on the block in the retainer and are put in the press which is modified by the omission of the openings 13 and by the provision of openings or grooves in the plunger 9 to receive 70 the prongs of the attaching plate. Otherwise the method is that previously stated.

From the above it will be apparent that I have devised a very compact buffer of great usefulness for various purposes which may 75 readily be driven into the surface to which it is sought to be attached or into a socket, which is almost as durable as steel and which has great hardness and pressure and wear resisting power while having no injurious effect on polished floors and being noiseless.

What I claim as my invention is:

1. A buffer comprising a retainer having a hole in its bottom leaving a pressure resisting flange surrounding said hole, a block of compressible fibrous material formed into a hard contact button by compression against the flange and through the hole and by further compression of the part thus 85 forced through the hole, a backing plate for the block, means on the retainer for retaining the backing plate and block in position with the block compressed, and means for attaching the buffer.

2. A buffer comprising a retainer having a hole in its bottom, a block of unsized felt formed by having its edge supported, gripped and compressed and its inner part at the same time materially displaced with 90 respect to said edge by compression into a cavity surrounded by a support for the edge and by further compression and shaping of said inner part, means for permanently holding in the retainer the felt block as thus 95 formed with its inner part projecting through the hole in the retainer to act as a contact button, and means for attaching the buffer.

3. A buffer comprising a retainer having 100 a hole in its bottom, a block of unsized felt larger than said hole and of substantially uniform thickness compressed against the bottom of the retainer and through the hole 105 therein and formed into a hard contact button, and a backing plate therefor permanently secured to said retainer.

4. A buffer comprising a retainer having a hole in its bottom, a block of felt larger than said hole having its outer part gripped 120 against the bottom of the retainer adjacent the hole and its inner part materially displaced with respect to its outer part through said hole by compression of the block against the bottom and through the hole, means for attaching the buffer, and means for permanently fastening together said retainer, compressed block, and attaching means.

5. A buffer comprising a retainer, a pad 125

or cushion therein, a backing plate for said pad or cushion having a raised portion and a flange below the same surrounding it, and a plate on the under side of the backing plate within the raised portion and having prongs projecting therethrough, the upper edge of the retainer being bent down upon the flange to hold the parts permanently in assembled relation with the turned down

edge and raised portion in substantially the same plane.

Signed by me at Syracuse, N. Y., county of Onondaga, this 29 day of July 1909.

ROBERT P. HERON.
